UNITED STATES PATENT OFFICE.

ALLEN B. MAULL, OF BALTIMORE, MARYLAND.

GUIDE APPARATUS.

1,108,457.

Specification of Letters Patent. Patented Aug. 25, 1914.

Application filed May 21, 1912. Serial No. 698,771.

To all whom it may concern:

Be it known that I, ALLEN B. MAULL, a citizen of the United States, residing at Baltimore, in the State of Maryland, have 5 invented certain new and useful Improvements in Guide Apparatus, of which the following is a specification.

This invention relates to an improved guide chart or map and holder therefor.

10 One of the objects of the invention is to provide an improved device which will aid persons to find their way through strange cities or localities and to enable them to readily determine approximately the distance 15 from a central place or the distance from a second to a third or more places.

Another object is to provide an improved chart, map or guide apparatus especially useful for tourists in vehicles whereby the 20 same may be sustained in a convenient place and in view for reference at all times.

With these and other objects in view the accompanying drawing illustrates the inventive idea wherein.

25 Figure 1, shows a face view of the chart or guide and the holder. Fig. 2, illustrates the same partly in side elevation and partly in vertical cross-section. Fig. 3, shows an enlarged sectional detail through the central 30 portion of the holder and shows the means for holding the chart or map proper in place. Fig. 4, illustrates an enlarged detail of the radially-sliding scale bar and the connection of the same with the holder, and 35 Fig. 5, shows an enlarged cross-sectional detail through the scale bar to illustrate the sliding and pivoted connection of the extension arm therewith.

Referring to the drawing by numerals, 1, 40 designates a bracket or disk which may be attached to the floor, dash or other desirable part of a vehicle such, for example, as an automobile,—the bracket or disk having suitable perforations, 2, therein for bolts or 45 screws. At one side the bracket or disk is provided with suitable spaced-apart lugs, 3, between which one end of a post or support, 4, extends and a clamping bolt and nut, 5, serves to adjustably clamp the post to the 50 lugs. A rod, 6, telescopically engages the post, 4, and a clamp, 7, serves to bind the two together after a longitudinal adjustment of them has been made. The upper end of the rod, 6, is provided with a clamp head, 8, 55 which pivotally sustains a short arm, 9, and a clamping nut, 10, serves to secure the head

in the adjusted position while a set-screw, 11, rigidly binds the head to the rod, 6. By means of the construction set forth the post, 4, may be swung with respect to bracket 60 disk, 1; rod, 6, may be adjusted in post, 4, and arm, 9, may be tilted with respect to rod, 6. A plate, 12, has a stud, 13, at one side which enters a socket, 14, in the outer end of arm, 9, and is held therein by a set 65 screw, 15, and at the other side said plate has a centering pin, 16, which projects outwardly therefrom, as clearly shown in Fig. 3. The pin, 16, and plate, 12, sustain a circular holder, 17, which latter has a rim flange, 18, 70 with an inturned edge, 19, which overlies the holder proper, and the rim-flange, 18, of the holder is provided at intervals with circumferential slots, 20, through which the corners, 21, of a sheet guide, map or chart, 22, 75 may be projected while the body of the guide will lie against said holder. A scale bar, 23, extends diametrically across the holder, 17, said bar being provided with a circular head, 24, with a socket, 25, in its 80 inner side,—the head being so positioned on the scale bar that its socket will register with the central pin, 16. A perforation, 26, is provided in the center of the guide or chart through which the pin, 16, projects. 85 The scale bar, 23, carries a hinge clip, 27, at one end,—the hinge forming a pivot for the bar to swing on and the clip serving to slidably connect the hinge with the rim-flange, 18, of the holder. By means of this construction 90 the scale bar is slidably connected at one end to the rim flange of the holder and is also hinged at the same end so as to swing toward and from the holder. The opposite end of the scale-bar, 23, is provided with an 95 outwardly-bent portion, 28, which projects beneath the inturned edge, 19, of the rim flange and serves to hold said bar in a clamped position over the guide or chart. Obviously by bowing or pulling the scale bar 100 outwardly at the center the free end, 28, will become disengaged from the rim-flange whereupon the bar may be swung outwardly on the hinge, as shown in broken lines in Fig. 2, and the guide or chart, 22, may then 105 be removed or inserted as desired.

The scale bar, as its name implies, is provided with a scale, 29, the object of which will presently be set forth. A head, 30, is slidably mounted on the scale bar and a 110 scale arm, 31, is pivotally connected to the head and extends laterally therefrom. In

the present instance a longitudinal slot, 32, is provided on the scale bar and the head has the form of a clip which passes through the slot and has its two ends bent laterally so as to project over the scale bar and form a pivot connection for the end of scale arm, 31, as shown in detail in Fig. 5. It will thus be seen that the scale bar is sustained so as to turn from a central point on the 10 guide or chart and that the scale arm is connected to said bar in such a way that its connected-end may be moved longitudinally on the bar toward or from the center of the guide.

15 In the present instance the scale bar has a compass, 32, which is attached to the head, 24, at the center of the guide or chart which enables the points of the compass to be readily ascertained when viewing the guide. 20 The guide, chart or map is also provided with signs or marks as shown at, 33, to indicate compass direction thereon.

25 The guide or map, 23, shown in the present example is illustrative of the State of Maryland as an example, and the city of Baltimore, is located as the central point from which the scale-bar, 23, operates. If it is desired to determine the distances from Baltimore to Annapolis and then from Annapolis to Washington the scale bar will be turned so that the slotted end thereof will extend radially from the center or Baltimore and project across Annapolis; the head, 30, will then be moved along the scale 30 bar until it will have position over Annapolis and the pivoted scale-arm, 31, will then be swung so as to extend from Annapolis to Washington. Thus it will be seen that the distance from Baltimore to Annapolis 35 may be read on the radial scale bar and the distance from Annapolis to Washington will be read on the scale arm, 31.

40 Having thus described my invention what I claim and desire to secure by Letters Patent is:—

45 1. A guide apparatus of the character described comprising a holder provided with means for removably holding a map or chart, and a distance scale bar pivotally connected to said holder and movable away therefrom.

50 2. A guide apparatus of the character described comprising a holder, and a scale bar pivotally connected to said holder and movable away therefrom, and means for permitting relative rotation of said scale bar and said holder.

55 3. A guide apparatus of the character described comprising a holder, and a scale bar pivotally connected to said holder and movable away therefrom, said pivotal connection being provided with means for permitting said scale bar to rotate over the face of said holder.

60 4. A guide apparatus of the character de-

scribed comprising a holder provided with means for removably holding a map or chart, a pivot member slidably connected with said holder, and a distance scale bar connected with said pivot member.

65 5. A guide apparatus of the character described comprising a holder, a pivot member slidably connected with said holder, a scale bar connected with said pivot member, said holder being also provided with a stationary pivot member arranged to engage said scale bar.

70 6. A guide apparatus of the character described comprising a circular holder, and a scale bar having one end pivotally and slidably connected with the edge of said holder.

75 7. A guide apparatus of the character described comprising a holder, and a scale bar having one end pivotally and slidably connected with the edge of said holder, said holder being provided with a pivot pin arranged to engage said bar at a point between the ends of the latter.

80 8. A guide apparatus of the character described comprising a holder provided with a circular flange, and a scale bar extending diametrically across the space surrounded by said flange and having one end slidably connected with the latter.

85 9. A guide apparatus of the character described comprising a holder provided with a circular flange, a pivot member slidably connected with said flange, and a scale bar having one end connected to said pivot member.

90 10. A guide apparatus of the character described comprising a holder provided with a circular flange, a scale bar extending diametrically across the space surrounded by said flange and having one end slidably connected with the latter, said holder being provided with a pivot pin for engaging said scale bar between the ends of the latter.

95 11. A guide apparatus of the character described comprising a circular holder, a scale bar pivotally connected to the periphery of said holder and movable away therefrom, and a scale arm adjustably connected with said scale bar.

100 12. A guide apparatus of the character described comprising a holder, a scale bar pivotally connected to said holder and movable away therefrom, said pivotal connection being provided with means for permitting said scale bar to rotate over the face of said holder, and a scale arm adjustably connected with said scale bar.

105 13. A guide apparatus of the character described comprising a holder, a scale bar pivotally connected to said holder and movable away therefrom, said pivotal connection being provided with means for permitting said scale bar to rotate over the face of said holder, and a pivoted scale arm adjustable longitudinally of said scale bar.

14. A guide apparatus of the character described comprising a holder, a scale bar having one end pivotally and slidably connected with the edge of said holder, said

5 holder being provided with a pivot pin arranged to engage said bar at a point between the ends of the latter, and a scale arm adjustably connected with said scale bar.

15. A guide apparatus of the character described comprising a circular holder, a scale bar having one end pivotally and slidably connected with the edge of said holder, said bar being provided with a longitudinal slot, a head slidably engaging said slot, and 15 a scale arm pivotally connected with said head.

16. A guide apparatus of the character described comprising a circular holder, a scale bar having one end pivotally and slidably connected with the edges of said holder, said bar being provided with a longitudinal slot, and a pivoted scale arm provided with means for adjustably engaging said slot.

17. In a guide apparatus the combination 25 with a holder having a circular flange, of a scale bar having one end slidably connected to said flange; means carried by said holder for pivotally engaging the scale bar between its ends and a scale arm pivotally carried 30 by said bar.

18. In a guide apparatus the combination with a holder having a circular flange, of a

scale bar having one end slidably connected to said flange; a head slidably connected to said bar, and a scale arm pivoted to said 35 head.

19. In a guide apparatus the combination with a holder having a circular flange, of a scale bar having one end slidably connected to said flange; means carried by said holder 40 for pivotally engaging the scale bar between its ends; a head slidably carried on the said bar and a scale arm pivotally connected at one end to the head.

20. In a guide apparatus the combination with a holder having a circular flange with a plurality of circumferential slots therein to receive the edges of a guide sheet, of a scale arm pivotally connected to the holder at the center of the circular flange and a 50 scale arm pivotally connected by one end to the scale bar.

21. In a guide apparatus the combination with a supporting bracket, of a guide holder; means for adjustably connecting the 55 bracket and holder; a scale bar pivotally carried on the holder and a scale arm adjustably connected with the scale bar.

In testimony whereof I affix my signature in presence of two witnesses.
